UNITED STATES PATENT OFFICE.

THOMAS HAWKINS, OF LONDON, ENGLAND.

APPARATUS FOR EMBOSsing PAPER OR THE LIKE.

SPECIFICATION forming part of Letters Patent No. 773,496, dated October 25, 1904.

Original application filed November 13, 1902, Serial No. 131,147. Divided and this application filed December 11, 1903. Serial No. 184,803. (No model.)

To all whom it may concern:

Be it known that I, THOMAS HAWKINS, a citizen of the United States of America, residing at 40 Marchmont street, Russell Square, London, England, have invented certain new and useful Improvements in Apparatus for Embossing Paper or the Like, of which the following is a specification, the subject of this application having originally formed part of and 10 having been divided from an application for a patent filed by me on November 13, 1902, Serial No. 131,147, and entitled "Improvements in apparatus for embossing and producing or perforating labels, name-plates, or other 15 sheets or strips and in dies therefor."

This invention relates to apparatus for embossing paper and the like, and has been designed with a view to producing a cheap and efficient device whereby such material may 20 be readily embossed. The device is easily portable and can be carried in the pocket.

The invention consists, broadly, in the provision of duplicate embossed strips which are backed up for additional strength, one set of 25 the strips being detachably secured to a base-piece and the other set being also detachably secured to a frame which is hinged to the base-piece and remains normally away therefrom.

30 The accompanying perspective view illustrates a convenient manner of carrying out the invention.

A is the base-piece, and B B are the embossed strips which are detachably secured 35 thereto, say, by means of screws C C.

D is a frame having extensions E E, which are made of resilient material and have return-pieces F F secured by screws G G to the base-piece A, the frame D remaining normally raised, as shown. A set of embossed strips H H, which are duplicates of the strips 40 B B, are temporarily secured to the frame D—say by means of thumb-screws J J—in such a manner that the embossments on both sets 45 of strips correctly register with one another.

Each pair of corresponding strips may be embossed by my machine which is the subject of the application for patent, Serial No. 131,147, aforesaid or by any other suitable

embossing-machine, of which there are several 50 well-known types.

After embossment the non-working faces of the strips are backed up for the purpose of strengthening them by filling or leveling up such faces with solder or some other suitable 55 substance, which prevents spreading or crushing of the embossments when pressure is applied thereto.

A fulcrum K is secured to the base-piece A and is provided with a pin L, upon which is 60 pivoted a lever M, carrying a platen N of sufficient size to cover the embossments O.

To use the apparatus, the material to be embossed is inserted between the lower and upper strips and is then embossed by depressing 65 the latter by means of the lever and platen. When the pressure is released, the upper strips will rise clear of the material.

Obviously any convenient number of pairs 70 of strips may be used.

As an alternative the base A may be dispensed with, in which case the pieces F F may be produced forwardly and the lower strips may be attached thereto, the fulcrum K being secured, say, to a piece bridging the gap between the pieces F F, such a construction of 75 embosser occupying less space than the form shown.

What I claim, and desire to secure by Letters Patent of the United States, is— 80

1. Apparatus for embossing comprising in combination a base-piece A, stationary embossed strips B, B upon said base-piece, a backing upon said strips B, B to strengthen them, means for securing said strips B, B to 85 the base-piece, a self-raising frame, means for securing said frame to the base-piece, strips H, H upon said frame said strips H, H, being embossed to correspond and adapted to correctly register with the strips B, B, means for 90 securing the strips H, H, to the frame and means for producing the required pressure for embossing.

2. Apparatus for embossing comprising in combination, a lower frame, stationary embossed strips B, B, upon said lower frame a backing upon said strips B, B, to strengthen them, means for securing said strips to said 95

frame, a self-raising upper frame, means for connecting said upper frame with said lower frame, strips H, H, upon said upper frame said strips H, H, being embossed to correspond and 5 adapted to correctly register with the strips B, B, means for securing the strips H, H, to the upper frame, and means for producing the required pressure for embossing.

3. Apparatus for embossing comprising in 10 combination a base A, backed-up embossed strips B, B, screws C, C, securing the strips B, B, to the base-piece A, frame D, extensions E, E, upon said frame D, return-pieces F, F, connecting the frame D to the base-piece

A, screws G, G, securing the pieces F, F, to 15 the base-piece A, backed-up embossed strips H, H, thumb-screws J, J, securing the strips H, H, to the frame D, fulcrum K mounted upon said base-piece, a pin L in said fulcrum, a lever M upon said pin, and a platen N upon 20 said lever adapted to produce the required pressure for embossing.

In witness whereof I have hereunto set my hand in the presence of two witnesses.

THOMAS HAWKINS.
